UNITED STATES PATENT OFFICE.

RAYMOND L. KINGSTON, OF DETROIT, MICHIGAN.

FLEXIBLE CONNECTER.

Application filed June 26, 1922. Serial No. 571,059.

This invention relates to flexible webbing formed into a loop to serve as a door stop, spring shackle or other connecting element, and its object is to provide a connector of this character which will be very flexible, which will not abrade enameled, varnished or painted surfaces, and which will have great strength.

This connector consists of a short length 10 of knitted or woven tubing folded upon itself intermediate its length and, if desired, having one or both of its edges tucked in between the folds so as to form an endless band, the band then being flattened and 15 sewed through to constitute two loops connected by a soft pliable strip of fabric. It also consists in the details of construction illustrated in the accompanying drawing and particularly pointed out in the claims.

20 In the accompanying drawing, Fig. 1 is a perspective view of a portion of a door and casing, and a door stop embodying the present invention. Fig. 2 is a perspective of this improved door stop. Figs. 3, 4, 5 25 and 6 are cross sections of flexible connectors embodying the present invention.

Similar reference characters refer to like parts throughout the several views.

Flexible connectors have been made by 30 convolutely winding a band and then pressing it together and sewing through the two sides or by riveting the two sides together. The result has not always been satisfactory as the rivets often tear out and the threads 35 break and permit the band to unwind.

In the present case a short length of woven or knitted tubing made of fibrous material, such as cotton, linen, wool or silk, is folded upon itself intermediate its ends 40 so that the sides lie flat against each other and then one or both ends are tucked in between the sides to form a band. In Fig. 3 a cross section of a folded band is shown comprising the two outer laps 1 and the inner laps 2. The band is then flattened to 45 constitute the loops 3 and intermediate portion 4 of the connector and the sides of the intermediate portion are sewed through by longitudinal lines 6 and transverse lines 5 50 of stitches. If the connector is to be used as a door stop, brackets 7 may be passed

through the loops 3 and attached to the casing 8 and door 9 by means of screws 10.

If desired, the connector may be enclosed by a wrapping 12 of finishing fabric, leather 55 or rubber, or which may be of the same material as the upholstering of the vehicle body. Instead of four laps such as shown in Fig. 3, the tube may be folded again to produce the outer laps 13, inner laps 14 and intermediate laps 15, as shown in Fig. 5. The original tubing is preferably woven with continuous woof threads and when great strength is desired the wires 16 may be woven into the fabric among the woof threads as indicated 60 in Fig. 4, these wires being in the form of helices in the original tubing and therefore substantially endless in the connector.

This endless connector can be made of great strength without destroying its flexibility and the softness of the original fabric 70 serves to prevent any scratching of the finish of the parts to which it is attached. The cut ends of the fabric tubes are preferably turned in out of sight so that rounded 75 edges alone are to be seen.

The details of the construction of this connector and its proportions may be further modified by those skilled in the art without departing from the spirit of my invention 80 as set forth in the following claims.

I claim:

1. A connector comprising an endless band folded together to constitute terminal loops and a connecting portion between 85 them, the band being formed from a section of tubing folded upon itself intermediate its ends, the two parts of the band constituting the connecting portion being sewed together.

2. A connector comprising an endless band folded together to constitute terminal loops and a connecting portion between them, the band being formed from a section of tubing folded upon itself intermediate 90 its ends, the two parts of the band constituting the connecting portion being sewed together by longitudinal and transverse lines of stitches.

3. A connector comprising an endless band folded together to constitute terminal 100 loops and a connecting portion between them, the band being formed from a section of

tubing folded upon itself intermediate its ends and having such ends tucked in between the resulting sides, the two parts of the band constituting the connecting portion being sewed together.

4. A connector comprising an endless band folded together to constitute terminal loops and a connecting portion between

them, the band being formed from a section of tubing folded upon itself intermediate its ends, the two parts of the band constituting the connecting portion being sewed together, said tubing being formed with circumferential woof threads and reinforcing wires woven in among the woof threads.

RAYMOND L. KINGSTON.
